UNITED STATES PATENT OFFICE.

MAXIMILIAN CHARLES SCHWEINERT, OF WEST HOBOKEN, NEW JERSEY.

COMBINED VALVE-CAP AND PUMP-COUPLING.

1,261,302.

Specification of Letters Patent.

Patented Apr. 2, 1918.

Application filed January 18, 1916. Serial No. 72,878.

To all whom it may concern:

Be it known that I, MAXIMILIAN CHARLES SCHWEINERT, a citizen of the United States of America, residing in West Hoboken, in the county of Hudson and State of New Jersey, have invented certain new and useful Improvements in Combined Valve-Caps and Pump-Couplings, of which the following is a specification.

10 This invention relates to pneumatic tire or similar valves, and aims to provide certain improvements therein.

The standard pneumatic tire valve is usually provided with a cap adapted on one side to screw down over the valve casing and having a packing designed to make a tight joint with the end of the casing. In axial alinement therewith is usually provided a screw-driver projection by means of which the common valve insides may be inserted into and removed from the casing. According to the present invention I provide a valve cap of this type which has an additional function of serving as a pump coupling, by means of which the pump may be connected with the valve casing. Ordinarily such a function is not necessary, since pump couplings are usually adapted to screw directly on the casing when the valve cap is removed. Many pump couplings are, however, (and particularly abroad) constructed to screw over a much smaller valve nipple than is usual in connection with the standard Schrader valve, so that the pump 25 is not fitted for direct application to the valve casing. It is necessary in such cases to provide a supplementary pump coupling in order to fit such pumps for this use. Such supplementary pump couplings are apt to be lost or mislaid and one of the objects of the present invention is to provide a coupling of this character which will be a part of the valve cap, which latter is always in place upon the valve except during inflation or deflation.

In the drawings wherein I have illustrated several forms of the invention,—

Figure 1 is a diametrical section of a cap constructed according to the present invention, the cap being shown in connection with

a pump and valve, and being in position to act as a coupling member.

Fig. 2 is an elevation of the cap looking from left in Fig. 1.

Fig. 3 is a similar elevation, looking from the right.

Fig. 4 is a sectional view of another form of cap.

Fig. 5 is a top view of Fig. 4.

Fig. 6 is a sectional view of another form of cap.

Fig. 7 is a sectional view of still another form.

Referring first to Figs. 1 to 3, let A indicate the cap as a whole having a screw-threaded recess B adapted to fit over the end of a standard valve C. D is a packing adapted to make a tight joint with the top face E of the valve casing and thus prevent any leakage through the casing. Axially opposite the recess B is a screw-driver projection F which is adapted to enter the casing and to be used as a tool to unscrew the valve insides G. At the side of the cap is provided a screw-threaded projection H which is adapted to be connected to a coupling piece I of a pump tube J. When the coupling piece I is constructed for engagement with a valve nipple which is of different dimensions from the nipple C, the projection H will correspond in its dimensions. As shown, the coupling piece is intended primarily for a much smaller nipple than C, and consequently the projection H will correspond to the dimensions of such nipple. In the construction shown the projection H has a tapered end K, and the coupling piece I has a tapered seat L for forming an approximately tight joint with the projection. On the opposite side of the cap is provided a projection M which is of proper dimensions to enter within the nipple C of the standard valve (or it may be to screw over the exterior of such nipple) and a packing such as N is provided for bearing against the upper face E of the nipple for forming a tight joint therewith. Between the projection H and the projection M is a passage, such as O, adapted to conduct air from the pump tube to the valve.

In Fig. 4 a similar construction is shown with the exception that instead of the screw-driver projection F' being located in axial alignment with the body of the cap it is located at one side, while the projection M' occupies the position of the screw-driver projection shown in Fig. 1. The pump projection H in this construction is located as is shown in Fig. 1. The connecting bore O' in this construction is an angled passage.

In Fig. 6 the arrangement is such as to render the several projections more compact, the pump connection H^2 being in axial alignment with the body of the cap while the valve projection M^2 is located at one side and at an acute angle to the body of the cap. The bore O^2 is angular, as shown. The screw-driver projection F^2 is arranged on the opposite side from the valve projection and preferably in line therewith.

In Fig. 7 the pump projection H^3 is located as in Fig. 6, as is also the screw-driver projection F^3 . The valve projection M^3 is, however, arranged at right angles to the body of the cap.

It is obvious that several other arrangements of these projections may be made.

The construction of Fig. 6 is perhaps the most compact arrangement, and better adapted for the performance of the several functions involved.

While I have shown and described several forms of the invention, it will be understood that I do not wish to be limited thereto, since various changes may be made therein without departing from the invention.

What I claim is:—

1. A combined cap and inflation coupling comprising a part adapted to make a screw-threaded engagement with a valve shell to close the end of the same, and an adapter comprising means for engaging the valve, means for engaging a pump which does not fit the valve, and a passage leading from one of said means to the other.

2. A combined cap and inflation coupling comprising a part adapted to make a screw-threaded engagement with a valve shell to close the end of the same, and an adapter comprising a projection adapted to be connected with a pump which does not fit the valve, a projection adapted to be connected with the valve, and a passage between said two last-named projections.

3. A combined cap and inflation coupling comprising a part adapted to make a screw-threaded engagement with a valve shell to close the end of the same, and an adapter comprising a projection adapted to be connected with a pump which does not fit the valve, a projection adapted to be connected with the valve, a passage between said two last-named projections, and a third projection constituting a tool.

4. A combined cap and inflation coupling comprising a part adapted to make a screw-threaded engagement with a valve shell to close the same, and an adapter comprising a screw-threaded projection adapted to fit the valve, a projection of smaller diameter adapted to fit a pump coupling which does not fit the valve, and a passage between said two last-named projections.

5. A combined cap and inflation coupling comprising a part having a recess formed with an internal screw-thread and having a packing washer and constituting a cap for a valve to close the same and an adapter comprising a screw-threaded projection of small diameter adapted to be connected with a pump which does not fit the valve, and a screw-threaded projection of larger diameter adapted to fit the valve.

6. A combined cap and inflation coupling comprising a part having a recess formed with an internal screw-thread and having a packing washer and constituting a cap for a valve to close the same, and an adapter comprising a screw-threaded projection of small diameter adapted to be connected with a pump which does not fit the valve, a screw-threaded projection of larger diameter adapted to fit the valve, and a passage leading from one projection to the other.

7. A combined cap and inflation coupling comprising a part having a recess formed with an internal screw-thread and having a packing washer and constituting a cap for a valve to close the same, and an adapter comprising a screw-threaded projection of small diameter adapted to be connected with a pump which does not fit the valve, a screw-threaded projection of larger diameter adapted to fit the valve, a passage leading from one projection to the other, and a screw-driver projection.

8. A combined cap and inflation coupling comprising a part having a recess formed with an internal screw-thread and having a packing washer and constituting a cap for a valve to close the same, and an adapter comprising a screw-threaded projection of small diameter adapted to be connected with a pump which does not fit the valve, a screw-threaded projection of larger diameter adapted to fit the valve, a passage leading from one projection to the other, and a screw-driver projection, and one of said projections being in line with said first-named part.

9. A combined cap and inflation coupling comprising a part having a recess formed with an internal screw-thread and having a packing washer and constituting a cap for a valve to close the same, and an adapter comprising a screw-threaded projection of small diameter adapted to be connected with a pump which does not fit the valve, a screw-threaded projection of larger diameter

adapted to fit the valve, a passage leading from one projection to the other, and a screw-driver projection, one of said projections being in line with said first-named part and 5 said two remaining projections being in axial alinement.

In witness whereof, I have hereunto signed

my name in the presence of two subscribing witnesses.

MAXIMILIAN CHARLES SCHWEINEET.
